JOHN E. GOODWILLIE, OF BROOKLYN, NEW YORK, ASSIGNOR TO INGERSOLL-RAND COMPANY, OF JERSEY CITY, NEW JERSEY, A CORPORATION OF NEW JERSEY.

SURFACE CONDENSER.

Application filed October 19, 1925. Serial No. 63,252.

This invention relates to surface condensers and its object is to cool and devaporize the uncondensable gases within the condenser.

5 In the largest sizes of condensers it is usually considered to be more efficient to cool and devaporize the uncondensable gases in a separate or auxiliary condenser. When this is done in the smaller sized condensers, 10 the expense of the apparatus is unwarranted and as a rule a condenser of slightly larger capacity is provided which will cool and devaporize the uncondensable gases in its lower sections. In that method the cooling 15 is not properly efficient since the air and gases are not properly separated from the steam and the air does not come in contact with the coolest portions of the cooling tubes. This invention provides an arrangement 20 by which the air is passed over the coolest portions of the tubes within the condenser to devaporize it as thoroughly as possible before passing to the vacuum pump.

The invention will be more clearly understood by reference to the following description taken in conjunction with the drawings, which include

Figure 1, a longitudinal vertical section of a condenser constructed in accordance 30 with the practice of the invention, and

Figure 2, a vertical longitudinal section of a modified form of the invention embodied in a condenser.

Referring to the drawings and more particularly to Figure 1, the condenser comprises a shell A having a steam inlet B and an outlet C for condensate. A plurality of tubes D are arranged preferably transverse to the path of the steam entering the inlet 35 B and supported at either end in tube sheets E, by which leakage of cooling water into the interior of the casing A is prevented. An inlet water head F is provided adjacent one of the tube sheets E which is supplied 40 with water from a suitable pipe G, and at the other tube sheet E, the condenser is provided with a discharge head H into which the water from the cooling tubes D is discharged. A pipe J is provided at the discharge head H to convey the water to a suitable cooling tank or other point to be disposed of. Between the ends of the tubes D a plate K is provided to support the tubes 45 against vibration and against distortion 50 from impact of the steam.

Theoretically, there should be no air in the steam entering the inlet B, but this condition is most unusual and air in various quantities depending upon the tightness of joints is almost always present. It is usual 60 to provide an exit for the air separate from the condensate outlet and at this exit it is necessary to provide a suitable vacuum pump which is adapted to exhaust the air from the interior of the shell in order to 65 maintain a vacuum therein.

In order that it shall not be necessary to provide a vacuum pump of capacity sufficient to handle steam exhausted with the air, that is, so that the capacity of the vacuum pump may be as small as possible to conserve power, it is desirable that the air drawn from the interior of the condenser be cooled to its smallest volume and devaporized as well. Preferably the air should be 70 led into a compartment separated from the steam in order that it shall not mingle therewith and carry off vapor to the vacuum pump. To this end means are provided to 75 lead the air to be devaporized from a portion of the condenser remote from the steam inlet and past the coolest ends of the cooling tubes D to an air outlet L.

In the embodiment shown in Figure 1 this means includes a curved plate or partition O, sealed at the sides of the casing A and at the top near the air outlet L, and curved from the top downwardly and toward the center of the casing A. Since the vacuum pump (not shown) is connected at the air outlet L, air will be drawn from below the lowermost bank of tubes D upwardly across the ends of the tubes D and out at the air outlet L. The air outlet L is preferably adjacent the cool end 80 of the condenser and remote from the condensate outlet, as for instance at the top of the shell A so that the air drawn out will pass the coolest ends of the tubes to condense the greatest possible quantity of 85 vapor in the air. It is seen that in the embodiment shown in Figure 1, the cross sectional area of the path of the air to the outlet L decreases in the direction of the outlet. This is considered theoretically 90 most desirable since the volume of the air being withdrawn decreases upon cooling and devaporizing.

In the embodiment shown in Figure 2, there is provided a partition P correspond-

ing to the partition O of Figure 1 which is simple to construct and install in the shell A. In this embodiment the partition P is a flat plate extending parallel to the tube sheet E forming a compartment therebetween for the passage of air to be devaporized. In some cases it may be that sufficient space will be provided in the passage between the partition P and the tube sheet E to accommodate the flow of air without excessive pressure loss due to friction.

It is understood that there should be a tight fit at the joints between the partitions O and P and the tubes D and at the walls of the casing A so as to prevent steam in appreciable quantities from leaking into the space adjacent the tube sheet E without passing around the lower end of the partitions O or P. Naturally there is a tendency for steam to leak at these points since the pressure is lower at the air outlet L than at the steam inlet B.

I claim:

25. 1. A steam condenser comprising a casing having a steam inlet and outlets for air and condensate, a plurality of water tubes arranged transverse to the direction of steam flow in the casing and interposed between the steam inlet and condensate outlet, and a partition forming a compartment within the casing at the cool ends of the water tubes, said compartment leading from

the space adjacent the condensate outlet to said air outlet.

2. A condenser comprising a casing having a steam inlet and outlets for air and condensate, a plurality of water tubes arranged transverse to the direction of steam flow in the casing, an outlet for air and uncondensable gases remote from the condensate outlet, and a partition forming a compartment within the casing at the cool ends of the water tubes, said compartment leading from the space adjacent the condensate outlet to said air outlet, said compartment being sealed from the main body of the condenser remote from the condensate outlet.

3. A condenser comprising a casing having a steam inlet and an outlet for condensate, a plurality of water tubes extending transverse to the direction of steam flow in the casing, an outlet for air and uncondensable gases remote from the condensate outlet, and a curved partition within the casing at the cool ends of the tubes forming a compartment leading from the space adjacent the condensate outlet to said air outlet, said partition sealing said compartment from the condensate outlet and the cross section of said compartment decreasing as it approaches the air outlet.

In testimony whereof I have signed this specification.

JOHN E. GOODWILLIE.
